UNITED STATES PATENT OFFICE.

HAYES GADDIE, OF WELLINGTON, KANSAS.

CULTIVATOR.

1,091,056.

Specification of Letters Patent. Patented Mar. 24, 1914.

Application filed February 27, 1912. Serial No. 680,223.

To all whom it may concern:

Be it known that I, HAYES GADDIE, a citizen of the United States, residing at Wellington, in the county of Sumner and State 5 of Kansas, have invented a new and useful Cultivator, of which the following is a specification.

This invention relates to cultivators, one of its objects being to provide means under 10 the control of the rider whereby the frame of the machine can be shifted forwardly or rearwardly with relation to the supporting wheels, thereby to balance the machine.

A further object is to provide improved 15 means for turning the wheels about vertical axes to guide the machine, the steering mechanism being operable by the person riding on the cultivator and being unaffected by the actuation of the balancing mechanism.

Another object is to provide improved 20 means whereby the cultivator shovels can be shifted vertically within the machine, said shovels being disposed in groups or 25 gangs and each gang being shiftable either with or independently of the next adjoining gang.

A further object is to provide means 30 whereby the cultivator blades or shovels can be shifted transversely of the machine so as to adjust them relative to the rows.

Another object is to provide a lock including means whereby the cultivator blades are automatically unlocked prior to their 35 transverse adjustment, the means for shifting or transversely adjusting the blades being employed for actuating the lock to hold said blades in any position to which they may be adjusted.

With the foregoing and other objects in view which will appear as the description proceeds, the invention resides in the combination and arrangement of parts and in the details of construction hereinafter 40 described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a plan view of the machine. Fig. 2 is a rear elevation thereof. Fig. 3 is a side elevation, one of the supporting wheels being removed

and the draft equalizer being shown in section. Fig. 4 is a perspective view of a portion of the steering mechanism. Fig. 5 is an enlarged view partly in rear elevation 60 and partly in section of a portion of the mechanism utilized for locking the cultivator blades against transverse movement and for shifting said blades transversely. Fig. 6 is a section on line A—B Fig. 5. 65 Fig. 7 is an enlarged transverse section through one of the guide members and the stem carrying block therein. Fig. 8 is a perspective view of one of the gang heads. Fig. 9 is a perspective view of one of the 70 cultivator beams. Fig. 10 is a view partly in side elevation and partly in section of one of the gang operating levers. Fig. 11 is a side elevation thereof, the segment of the main lever being removed. Fig. 12 is a section on line C—D Fig. 10.

Referring to the figures by characters of reference 1 and 2 designate front and rear parallel frame members each having depending parallel arms 3 at its ends. The 80 lower ends of the arms 3 at each side of the machine are connected by a guide member 4 parallel with the plane occupied by the frame members 1 and 2. Another guide member 5 is secured to the upper end portions of the arms 3 at each side of the machine and is parallel with the guide member 4 thereunder. As shown in the drawings 85 guide member 5 is slotted longitudinally and it is to be understood that the member 4 is to be similarly slotted. The two guide members 4 and 5 at each side of the machine are of like construction with the exception that the upper guide member 5 is provided, at each end, with an enlargement 6 fitting 90 snugly against the angle portions of the frame members 1 and 2, where the arms 3 extend downwardly through the enlargement 6, said enlargement being attached to the frame members 1 and 2 by U-bolts 7 100 or the like straddling the frame members. Thus it will be seen that the guide members 5 are fixedly connected to the frame members 1 and 2 as well as to the arms 3 and, therefore, rotation of the frame members is 105 prevented and the arms 3 are maintained at all times in fixed relation to each other. Any suitable means may be employed for securing the lower guide members 4 to the arms 3. Draft beams 8 are mounted on the 110 frame members 1 and 2 and carry a cross beam 9 to which is connected draft mecha-

nism indicated generally at 10. The beams 8 constitute additional means for holding the frame members 1 and 2 in proper relation to each other. An additional beam 18 5 is fixedly secured to the members 1 and 2 at points equidistant from the beams 8 and extends rearwardly from the frame member 2 so as to form an efficient support for the seat 19. A tie strip 20 connects the front 10 end of this beam 18 to the middle portion of the transverse draft beam 9. Brackets 21 are mounted on the beam 18 and a longitudinally extending shaft 22 is journaled in these brackets, said shaft being bent to 15 form an elongated crank 23. Oppositely extending arms 24 are formed on or secured to shaft 22 close to one end of the crank 23 and each arm is connected, by means of a downwardly extending link 25, to a foot 20 lever 26 which extends rearwardly to a point where it can be conveniently reached and actuated by a person occupying the seat 19. Thus it will be seen that upon the depression of one of the levers 26, one of the 25 arms 24 will be pulled downwardly and the shaft 22 rotated so as to swing crank 23 toward one side of the machine whereas, when the other lever 26 is depressed, crank 23 will be swung toward the other side of 30 the machine.

Mounted for sliding movement in the slot in each of the guide members 5 is a block 27 having ears 28 at the sides thereof and spaced therefrom to receive the side portions 35 of the guide member 5, as illustrated in Fig. 7. Anti-friction wheels 29 are journaled in the spaces between the block 27 and its ears 28 and constitute supports for the member 5. Another block 30 similar in all respects to 40 the block 27 is mounted within each of the lower slotted members 4 and extending through these upper and lower blocks 27 and 30 are stems 31 provided, at their lower ends, with spindles 32 arranged at right 45 angles thereto. These stems 31 are prevented from moving downwardly within the blocks 27 and 30 by collars 33 secured to the stems and bearing downwardly on the lower blocks 30. Upward movement of the stems 50 31 within the blocks is prevented by collars 34 bearing upwardly against the blocks, as shown in Fig. 2. Supporting wheels 35 are journaled on the spindles 32. It is to be understood that the stems 31 are adapted to 55 rotate within the blocks 27 and 30. Arms 36 are fixedly connected to the upper ends of the stems, these arms being parallel at all times and said arms are pivotally connected to a cross rod 37 which is parallel 60 with the members 1 and 2 and extends above the crank 23. A hanger 38 extends downwardly from the middle portion of the rod 37 and has a longitudinal slot 39 through which the crank 23 extends. Thus if will

be seen that when crank 23 is swang toward 65 one side, hanger 38 and rod 37 will be shifted therewith, thereby causing the arms 36 to swing laterally and to rotate the stems 31. The two supporting wheels 35 will thus be turned so as to steer the machine in the 70 desired direction.

The balancing mechanism constituting a part of this invention includes a rock shaft 40 journaled on the beams 8 close to the transverse draft beam 9 and this rock shaft 75 is provided, at its ends, with downwardly extending arms 41. Each of these arms has rearwardly diverging links 42 and 43 pivotally connected to it, the upper link being pivotally connected to the upper block 27 at 80 one side of the machine, while the other link 43, is pivotally connected to the lower block 30. An arm 44 extends upwardly from the shaft 40 adjacent the center thereof and is connected, as by means of a rod 45, to a lever 46 fulcrumed on the beam 18 where it can be easily reached by the occupant of the seat 19. This lever is provided with a toothed segment 47 adapted to be engaged by a pawl carried by the lever and whereby 90 the lever can be locked in any position to which it may be adjusted. The said pawl has been indicated generally at 48 in Fig. 3.

From the foregoing it will be seen that when lever 46 is shifted in one direction, 95 shaft 40 will be rotated so as to cause arms 41 to pull forwardly on the links 42 and 43. As these links are connected to the blocks 27 and 30 carried by the wheel supported stems 31, it will be seen that this action of 100 the shaft 40 will cause the said shaft 40, and the structure made up of the frame members 1 and 2, the beams 8 and 18, and the parts mounted thereon, to move rearwardly, thereby shifting the center of gravity. 105 When the movement of lever 46 is reversed, the operation will be reversed so that the center of gravity will be shifted forwardly relative to the supporting wheels 35.

Mounted on the frame members 1 and 2 110 at opposite sides of the central beam 18 are carriages 49. Each of these carriages consists of parallel side members 50 connected by cross strips 51 and 52. Grooved supporting wheels 53 are journaled in the end portions of the side strips 50 and bear downwardly on the frame members 1 and 2. Guide rods 54 extend transversely of the machine above and parallel with the frame members 1 and 2 and are supported at their 115 ends by brackets 55. These rods engage the upper portions of the rollers 53 so as to prevent said rollers and the carriages from becoming displaced relative to the frame members 1 and 2.

A rack bar 56 is extended from the rear end of each beam 8 to the rear end of the adjacent guide member 5, this rack bar be-

ing parallel with the rear frame member 2 and being extended under the rear portion of the adjacent frame 49.

Mounted on the rear end portion of one of the side members 50 of each carriage 49 is an inverted U-shaped guide 57 in which is formed a slot 58. A locking pin 59 is mounted to slide within this slot 58 and its lower end is held normally in engagement with the rack bar 56, by means of a spring 60 which is coiled about the pin 59 and bears at one end against the guide 57 and at its other end against a pin 61 or the like extending from the pin.

A yoke 62 is pivotally mounted at its center upon the upper portion of the pin 59 and extends downwardly so as to straddle the guide 57, said yoke having outstanding feet 63 which are slidably mounted within slotted guides 64 upstanding from the side strips 50 of the carriage. A rod 65 is pivotally connected to the yoke 62 at a point above the pin 59 and is also pivotally connected to an arm 66 extending radially from the rear end of a rock shaft 67 journaled on one side of the beam 18. A handle 68 extends rearwardly from the arm 66 to a point where it can be conveniently grasped by the occupant of the seat 19. Another arm 69 extends radially from the forward end of the shaft 67 and is connected, as by means of a link 70, to a bracket 71 secured on the front end of the side strips 50 of the carriage.

It will be apparent, by referring particularly to Figs. 5 and 6, that spring 60 holds the spring 59 normally in engagement with the rack 56 and, when the pin is thus disposed, the yoke 62 is located in a substantially upright position. When shaft 67 is rotated in one direction by means of handle 68, it either pulls or pushes through link 65, upon the upper end portion of yoke 62. The yoke is thus caused to tilt upon one of its legs 63 while the other leg is elevated within one of the guides 64. The yoke will thus pull on the pin 59 and lift its lower end out of engagement with the rack 56. This operation takes place during the first portion of the movement of shaft 67. During further movement of said shaft the foot at the elevated side of the yoke 62 comes into contact with the upper wall of the slot in guide 64 and is thus held against further movement in an upward direction. Consequently the yoke will be shifted laterally by the link 65 and will cause the carriage 49 to travel along the frame members 1 and 2, the rollers 53 serving to reduce friction to the minimum. As soon as the carriage has been shifted transversely of the machine in this manner until it has reached a predetermined position, handle 68 can be released whereupon spring 60 will return all of the parts

to their initial positions, pin 59 moving into engagement with the rack 56 and thus locking the carriage against further movement. By connecting shaft 67 at its two ends to the carriage 49 at the front and rear ends of the carriage, it will be seen that said carriage will be held parallel with the beams 8 while being shifted. The position of the pin 59 and the parts adjacent thereto when shifted out of normal position, has been indicated by dotted lines in Fig. 5.

Extending rearwardly from the transverse draft beam 9 are brackets 72 supporting a cross bar 73 which is preferably bolted or otherwise secured to the beams 8, as indicated at 74. Mounted on this bar in front of each carriage 49 is a pair of heads 75 each of which includes spaced ears 76 mounted for rotation on the bar 73. Two pairs of eyes 77 are formed on the heads 75, one eye of each pair being disposed above the other eye and spaced therefrom. A collar 78 is mounted on bar 73 between the ears 76 and is adapted to be held against movement on the bar 73 by means of a set screw 79 or the like. Each pair of eyes 77 has a stem 80 mounted for rotation therein and said stem is held against longitudinal movement relative to the eyes, by means of a collar 81 which is secured to the stem by a set screw 82 or the like. Stem 80 is formed at the upper end of a hanger 83 and the lower end of the hanger is provided with an upstanding stem 84. This upstanding stem extends through spaced ears 85 connected to the front end of a cultivator beam 86. Said ears are engaged by the stems 84 of both hangers 83 connected to the heads 75 in front of the cultivator beam, as will be apparent by referring to Fig. 1, and the ears 85 are held against movement along the stems 84 by collars 87 which are interposed between the ears and are fastened to the stems by set screws 88 or the like. As shown in Fig. 1 the distance between the stems 84 is the same as the distance between the stems 80 and the hangers 83 are therefore parallel and form, with the heads 75 and the ears 85, a parallelogram which permits the ears 85 to shift laterally relative to heads 75 but causes said ears to remain always substantially parallel with the bar 73. The cultivator beam 86 is preferably formed of a length of metal having its rear end portion offset laterally so as to be engaged by the standard 89 of the rear cultivator blade 90 of the gang connected to the beam 86. Another cultivator standard 91 is connected to the beam 86 in front of but to one side of the path of the blade 90. A metal strip 92 is secured to the rear end of the strip 86 and extends alongside of the rear portion of said strip 86 and is then offset, as at 93, where it is engaged by another standard 94

of a cultivator blade. Thus it will be seen that three standards are connected to the beam, said standards being out of alignment. It is to be understood of course that 5 any desired number of standards may be connected to the beam and these standards can be disposed in any relation desired.

A guide ear 95 is extended laterally from the strip 86 and is slidably mounted on a 10 guide rod 96 suspended from one of the side strips 50 of the carriage 49 above the beam. The cross strip 51 on each carriage has two alining shafts 97 journaled thereon, each shaft being provided at its outer 15 end with a radial arm 98 connected, by means of a link 99, to one of the beams 86 under the carriage. A forked lever 100 is loosely mounted on the two shafts 97 close to the adjoining ends thereof and 20 straddles a toothed segment 101 which is fixedly mounted on the carriage 49. A gear 102 is journaled within the forked lever 100 and meshes with the segment 101, this gear being normally engaged by a toothed slide 25 or pawl 103 mounted in the lever and connected, as by means of a rod 104, to a spring pressed lever 105. Pawl 103 serves to hold gear 102 against rotation and as this gear is constantly in mesh with segment 101, it 30 will be apparent that lever 100 is normally held against movement about the shafts 97.

A toothed segment 106 is secured to each side of lever 100 and is concentric with the shafts 97. Levers 107 are fixedly connected to the respective shafts 97 and close to the lever 100 and each of these levers 107 carries a spring pressed pawl 108 normally engaging the adjacent segment 106. Thus it will be seen that levers 107, pawls 108 and 40 segments 106 serve to normally lock the lever 100 to the two shafts 97. With the parts thus connected it will be seen that, by shifting lever 105 so as to raise the slide 103, gear 102 will be released and lever 100 can 45 then be swung about its fulcrum so as to cause the two levers 107, which are locked thereto, to rotate the shafts 97 simultaneously. The arms 98 extending from these shafts will, therefore, shift the links 99 so 50 as to raise or lower the beams 86. Should it be desired to shift one of the beams below carriage 49 independently of the other beam, the lever 107 controlling said beam is released from the segment 106 adjacent 55 thereto and shifted independently of lever 100. When the desired adjustment has been obtained said lever 107 can be locked to lever 100 by means of pawl 103 and segment 106.

60 It will be apparent that by using a machine such as herein described, the cultivator supporting structure can be shifted forwardly or rearwardly relative to the axis of rotation of the supporting wheels and 65 such movement will not interfere with the

steering mechanism. Furthermore the two carriages can be shifted toward or from each other so as to move the cultivator blades toward or away from the rows or so as to adjust them to rows at different distances apart. 70

What is claimed is:—

1. In a cultivator the combination with a frame including upper and lower guide members at the sides thereof, of supporting 75 wheels, means carried by the wheels and slidably mounted within and supporting the guide members, and means upon the frame for shifting the same relative to said wheel supported means. 80

2. In a cultivator, the combination with a frame including upper and lower guide members at the sides thereof, of supporting wheels, means carried by the wheels and slidably mounted within and supporting the 85 guide members, means upon the frame for shifting the same relative to said wheel supported means, and means upon the frame for simultaneously rotating the wheels about substantially vertical axes independently of the movement of the frame. 90

3. In a cultivator, the combination with front and rear frame members, arms depending from the ends thereof, and guide members connecting the upper and lower 95 portions of the arms, of supporting wheels, upwardly projecting stems supported by the wheels, blocks carried by the stems and slidably engaged by the guide members, a draft beam fixedly connected to the frame members, and means mounted on said beam and connected to the stems for shifting the guide members and the stems horizontally relative to each other. 100

4. In a cultivator, the combination with front and rear frame members, arms depending from the ends thereof, and guide members connecting the upper and lower portions of the arms, of supporting wheels, upwardly projecting stems supported by the 110 wheels, blocks carried by the stems and slidably engaged by the guide members, a draft beam fixedly connected to the frame members, means mounted on said beam and connected to the stems for shifting the guide members and the stems horizontally relative to each other, a carriage mounted to slide longitudinally of and upon the frame members, and a soil engaging device suspended from and movable with the carriage. 115 120

5. In a cultivator the combination with supporting wheels and upstanding stems carried thereby, of supporting elements carried by the stems, guide members movably mounted on said devices, frame members connected to and movable with the guide members, and means supported by the frame members for shifting the guide members relative to the supporting elements. 125

6. A cultivator including supporting 130

wheels, upstanding stems carried thereby, supporting elements carried by the stems, upper and lower guide members supported by and shiftable relative to the supporting elements, frame members connected by the guide members, a rock shaft, means supported by the frame members for actuating the rock shaft, said shaft being connected to the frame members, and means actuated by 5 the rock shaft and connected to the supporting elements, for shifting the guide members relative to said elements.

7. A cultivator including connected front and rear frame members, arms depending 15 therefrom, guide members connecting the arms and fixedly secured thereto, supporting wheels, elements slidably mounted within the guide members and supported by the wheels, and means for shifting the guide 20 members relative to said elements.

8. A cultivator including connected front and rear frame members, arms depending therefrom, guide members connecting the arms, elements slidably mounted within the 25 guide members, a stem mounted for rotation within the elements at each side of the cultivator, a supporting wheel connected to each stem, means for rotating the stems simultaneously within the elements, and means for 30 shifting the guide members relative to said elements.

9. In a cultivator, the combination with supporting wheels and upstanding stems carried thereby, of supporting elements 35 mounted on the stems, said stems being mounted to rotate within said elements, guide members carried by the supporting elements, frame members connecting the guide members, means for shifting the guide 40 members relative to the supporting elements, a shaft mounted for rotation above and movable with the frame members, said shaft including an elongated crank, means for actuating the shaft, and means slidably engaged and shiftable by the crank for simultaneously rotating the stems within the supporting elements.

10. A cultivator including a wheel sup-

ported structure including front and rear frame members, a wheel supported carriage 50 mounted to travel along the frame members, a rack fixed relative to said members, a locking pin normally engaging the rack to hold the carriage against movement, a rocking element connected to the pin, and means for 55 actuating said element to successively shift the pin out of engagement with the rack and move the carriage on the frame members.

11. A cultivator including a wheel supported structure having front and rear 60 frame members, a carriage mounted to travel longitudinally of said members, means for locking the carriage against movement, and means under the control of a single lever for successively unlocking the carriage and 65 shifting said carriage in either direction along the frame members.

12. In a cultivator a wheel supported structure including front and rear frame members, a carriage, supporting wheels 70 thereon and engaging the frame members, guides mounted above and engaging the wheels of the carriage to hold the carriage against displacement relative to the frame members, a rock shaft, means for actuating 75 the same, and connections between the shaft and the front and rear portion of the carriage for shifting the carriage along the frame members.

13. A cultivator including a wheel sup- 80 ported structure having front and rear frame members, a carriage movable longitudinally along the members, a laterally adjustable head mounted for rotation in front of the frame members, a beam, vertically 85 adjustable pivotal connections between the beam and head, and means upon the carriage for raising and lowering the beam relative thereto.

In testimony that I claim the foregoing as 90 my own, I have hereto affixed my signature in the presence of two witnesses.

HAYES GADDIE.
